UNITED STATES PATENT OFFICE.

VIRGINIUS Z. CARACRISTI, OF BRONXVILLE, NEW YORK, AND OLIVER D. H. BENTLEY, OF WEST ROXBURY, MASSACHUSETTS, ASSIGNEES TO B. F. STURTEVANT COMPANY, OF HYDE PARK, MASSACHUSETTS, A CORPORATION OF MASSACHUSETTS.

GOVERNOR MECHANISM.

1,310,738.

Specification of Letters Patent. Patented July 22, 1919.

Application filed April 9, 1917. Serial No. 160,744.

To all whom it may concern:

Be it known that we, VIRGINIUS Z. CARACRISTI and OLIVER D. H. BENTLEY, citizens of the United States, residing, respectively, at Bronxville, Westchester county, New York, and West Roxbury, Suffolk county, Massachusetts, have invented certain new and useful Improvements in Governor Mechanisms; and we do hereby declare the following to be a full, clear, and exact description of the invention, such as will enable others skilled in the art to which it appertains to make and use the same.

This invention relates to the governing of turbines or other engines, and particularly to the mechanism for connecting an engine with a throttling governor for the purpose of actuating the latter.

It has heretofore been proposed to connect an engine with a throttling governor by mechanism, for actuating the governor, which is adjustable to drive the governor at different speeds relative to that of the engine, whereby the normal speed of the engine may be varied without change in the normal speed of the governor. One object of the present invention is to produce a mechanism for this purpose in which the construction is such that the parts may be adjusted both for changes in speed and to compensate for wear without interference with the continued operation of the mechanism.

Another object of the invention, relating more particularly to its use in connection with a steam-turbine, is to produce a compact, simple and strong arrangement of the turbine and the governor-actuating mechanism.

The objects just mentioned, and others which will be set forth hereinafter, are attained by the construction hereinafter set forth and defined in the appended claims.

In the accompanying drawings, Figures 1 and 2 are respectively a front-elevation and a side-elevation of mechanism embodying the present invention, Fig. 1 being partly in section on the line 1—1 in Fig. 2, and Fig. 2 being partly in section on the line 2—2 in Fig. 1.

The invention is illustrated as embodied in apparatus comprising a steam-turbine of a well known form, this turbine having the usual casing 5, within which the turbine-

wheel or rotor 6 is inclosed. The nozzles 55 and other static members of the turbine are inclosed within and supported by the casing, and the casing is provided with an integral steam-chamber 7, through which steam is supplied to the several nozzles in 60 the usual manner. The steam is introduced to the steam-chamber through a governor-valve 8, controlled by a throttle-governor having centrifugal mechanism 9 of a familiar form. The governor is provided with 65 the usual horizontal drive-shaft 10, as shown in Fig. 1.

The governor is actuated by power derived from the turbine through variable-speed frictional drive-mechanism. As shown 70 in Fig. 2, one end of the turbine-shaft 11 carries a head 12, upon which a flat driving-disk 13 is mounted. This disk is engaged by a friction-wheel 14 of which the hub is mounted on a countershaft 15 parallel with 75 the face of the disk 13. The friction-wheel is splined to the countershaft, so that it may rotate the latter while being free to move along the countershaft and thus vary the distance between the axis of the disk and its 80 point of engagement with the friction-wheel.

The countershaft 15 is provided, at one end, with a pinion 16 which drives a gear 17 fixed on the drive-shaft 10 of the governor. A collar 30 is connected with the hub of the 85 friction-wheel 14 by ball-bearings, and this collar is pivoted to a bifurcated arm 18 projecting from a sleeve 19. This sleeve is screw-threaded, and is mounted upon a screw-threaded shaft 20 parallel with the 90 countershaft 15. The shaft 20 is connected, by bevel-gears 21, with a vertical shaft 22. By rotation of the shaft 22, manually or in any convenient manner, the shaft 20 may be rotated so as to cause the sleeve 19 to 95 move along the shaft and produce a traversing movement of the friction-wheel 14 on the countershaft. This movement results in a change in the speed of rotation imparted to the governor for any given speed of 100 rotation of the turbine-shaft.

For the purpose of supporting and incasing the movable parts of the change-speed mechanism a housing 23 is connected rigidly with one of the bearings of the turbine, 105 as shown in Fig. 2, and this housing incases the friction-disk 13. The housing is closed at the front by a plate 24, from which a

web 25 projects. This web has vertical end-
portions, as shown in Fig. 1, in which bear-
ings are formed for the shaft 20. A casing
26, which is open at the rear, is pivotally
5 supported upon the shaft 20, and is pro-
vided with bearings in which the counter-
shaft turns. The casing 26 is provided, at
the front, with a hand-hole which is nor-
mally closed by a pivoted cover 27. This
10 cover may be opened for convenient access
to the mechanism inclosed in the casing.
The plate 24 is provided with an opening,
as shown in Fig. 1, through which the fric-
tion-wheel projects into engagement with
15 the friction-disk. A lug 28 projects from
the bottom of the casing 26, and is perfor-
ated to embrace a stud 29 projecting from
the plate 24. A spring coiled around the
20 stud engages the lug and acts to swing the
casing 26 rearwardly about the pivotal
mounting provided by the shaft 20, so as to
press the friction-wheel constantly against
the disk with a uniform pressure and to take
25 up any wear which may occur in these mem-
bers.

Through the parts just described the
change-speed mechanism is firmly supported
by a direct connection with the turbine-cas-
ing, so that the two make a unitary con-
30 struction and are maintained always in
proper operative relation. Another val-
uable feature of the invention resides in the
relative arrangement of the shafts 10, 15
and 20. The shafts 10 and 20 are in axial
35 alignment, and consequently any swinging
movement of the casing 26, and the counter-
shaft 15 which is supported by it, does not
interfere with the correct meshing of the
gears 16 and 17. Owing to the fact that the
40 shaft 20 constitutes not only the means for
moving the arm 18 and the friction-wheel,
but also the pivotal support of the casing
26, the swinging movements of the casing do
not interfere with the actuation and control
45 of the friction-wheel by the shaft 20.

The invention is not limited to the em-
bodiment described and illustrated in the
accompanying drawings, but may be em-
bodied in various other forms within the
50 scope of the following claims.

Having now described the invention and
the preferred form of practising it, it is
definitely stated in its true scope in the fol-
lowing claims.

55 What is claimed as new is:—

1. The combination, with an engine, and
a governor provided with a drive-shaft, of
a countershaft; a support in which the coun-
tershaft is journaled parallel with said
60 drive-shaft, said support being movable
about an axis coincident with the axis of the
drive-shaft; a friction-wheel splined on the
countershaft; a frictional drive-member
with which the friction-wheel co-operates,
65 said drive-member being connected with and

actuated by the engine; gears connecting the
governor drive-shaft with the countershaft;
means for moving said support as aforesaid,
to regulate the engagement of the friction-
wheel with the frictional drive-member; and
70 means for moving the friction-wheel along
the countershaft to vary its point of engage-
ment with the drive-member.

2. The combination, with a governor pro-
vided with a drive-shaft, of a support ar-
ranged to swing about an axis substantially
coincident with the axis of said drive-shaft;
a countershaft journaled on said support
parallel with said axis; gears connecting the
drive-shaft and the countershaft; a friction-
wheel splined to the countershaft; a driving-
member in frictional engagement with the
friction-wheel; a screw-threaded shaft sub-
stantially coaxial with the pivotal movement
of said support; and means, for moving the
friction-wheel along the countershaft, com-
prising a member connecting the friction-
wheel and the threaded shaft and having a
screw-threaded engagement with the latter.

3. The combination, with a governor, of
a screw-threaded shaft; a support arranged
to swing about the axis of said shaft; a
countershaft, journaled in the support, par-
allel with the threaded shaft; a friction-
wheel splined on the countershaft; a driv-
ing-member in frictional engagement with
the friction-wheel; means for swinging said
support to maintain such frictional engage-
ment; a shifting member connected with the
friction-wheel and threaded upon the 100
threaded shaft, said member being adapted
to cause a traversing movement of the fric-
tion-wheel when moved by rotation of the
threaded shaft; and driving connections, be-
tween the countershaft and the governor, 105
adapted to yield to swinging movement of
the support and the countershaft.

4. The combination, with a governor, of
a frictional driving-member; a frictional
driven member; means, including a rotary 110
shaft, connected with the driven member to
cause a traversing movement thereof to vary
the speed with which the driven member is
actuated; a housing inclosing said frictional
members and comprising a stationary part 115
and a part pivoted to the stationary part on
the axis of said shaft; a countershaft, on
which the driven member is mounted, jour-
naled on the pivoted part of the housing;
and driving connections between the counter- 120
shaft and the governor.

5. The combination with an engine of
a governor therefor provided with a drive
shaft, a counter-shaft connected to the drive
shaft, a friction disk driven from the en-
gine, a friction wheel carried by the counter-
shaft for rotating said shaft, the wheel be-
ing adjustable across the face of the disk,
and a pivoted support for the bearings for
the counter-shaft tending to swing said shaft 125

toward the disk to maintain said shaft parallel with the face of the disk and the friction wheel in yielding contact with the friction disk.

5 6. The combination with an engine of a governor provided with a drive shaft, a counter-shaft connected to the drive shaft, a friction disk fixed upon the engine shaft, a friction wheel carried by the counter-shaft
10 and adjustable across the face of the disk, a main housing inclosing the disk and provided with an aperture through which the friction wheel projects to contact with the friction disk, and a supplemental housing
15 for the friction wheel.

7. The combination with an engine of a governor provided with a drive shaft, a counter-shaft connected to the drive shaft, a friction disk fixed upon the engine shaft,
20 20 a friction wheel carried by the counter-shaft and adjustable across the face of the disk, a main housing held in fixed position, and a supplemental housing pivotally supported

upon the main housing carrying the counter-shaft and inclosing the friction wheel. 25

8. The combination with an engine of a governor provided with a drive shaft, a counter-shaft connected to the drive shaft, a friction disk fixed upon the engine shaft, a friction wheel carried by the counter-shaft 30 and adjustable across the face of the disk, a main housing held in fixed position, a threaded shaft rotatably mounted on the main housing, a supplemental housing pivoted to swing about the axis of the threaded shaft and carrying the counter-shaft and inclosing the friction wheel, and a threaded sleeve mounted on the threaded shaft and connected with the friction wheel for adjusting the latter across the face of the friction 35 disk. 40
